EXTINGUISHER FOR CAR ASH TRAY
Billy E. Fox, 1924 Woodstock Way, Sacramento, Calif.
Filed Dec. 2, 1964, Ser. No. 415,283
7 Claims. (Cl. 131—237)

This is a continuation in part of application Serial No. 184,843, filed April 3, 1962, now abandoned.

The invention relates to an extinguisher for a car ash tray, and has as its primary object the provision of a means associated with a conventionally mounted car ash tray whereby upon opening the ash tray part way and placing a cigarette therein closure of the ash tray automatically extinguishes the cigarette butt, thus precluding the burning of the butt in the tray, and resultant smoke in the vehicle.

An additional object of the invention is the provision of a device of this character which may be readily associated with any conventional vehicle ash tray, and which will serve, by means of a movable plate, automatically operable by closure of the ash tray to compress the butt between the plate and the front of the ash tray, thus effectively extinguishing the same.

Still another object of the invention is the provision of a device of this character wherein after the butt is crushed to extinguish the same, the pressure on the plate is automatically relieved by the movement of the ash tray from its normal vertical position within the vertical dash panel of the automobile to a full open position, and the extinguished butt falls upon a rearwardly downwardly sloping plate and then from the plate to the bottom of the ash tray, so that when the tray is closed and then reopened, the space for extinguishing the cigarette is emptied and readily available for the provision of a further cigarette.

An additional object of the invention is the provision of such a device which is sturdy and durable in construction, reliable and efficient in operation, and relatively simple and inexpensive to manufacture and assemble as well as to apply to existing ash trays.

Other objects will in part be obvious and in part be pointed out as the description of the invention proceeds and shown in the accompanying drawings wherein:

FIGURE 1 is a front plan view, partially broken away, of a vehicle ash tray embodying the extinguisher of the instant invention in fully closed position, certain concealed parts being indicated by dotted lines, and a fragmentary portion of the dashboard mounting of the ash tray being indicated.

FIGURE 2 is a sectional view taken substantially along the line 2—2 of FIGURE 1 as viewed in the downward direction indicated by the arrows.

FIGURE 3 is a sectional view taken substantially along the line 3—3 of FIGURE 1 as viewed in the direction indicated by the arrows, a position of maximum opening being indicated in dotted lines; and

FIGURE 4 is a view similar to FIGURE 3 showing a position of partial opening.

Similar reference characters refer to similar parts throughout the several views of the drawings.

Having reference now to the drawings in detail, there is generally indicated at 10 a conventional vehicle ash tray which is pivotally mounted on pivots 11 in a suitable recess in the dashboard or front or rear panel 12 of a motor vehicle. The recess includes a top wall and two vertical parallel side walls. The side walls have grooves 31 to accommodate pivots 11.

The ash tray when in use is rotated between the closed position shown in full lines in FIGURE 3 completely contained within the dashboard, through the cigarette butt receiving partially open position shown in FIGURE 4, to

2

the maximum open and butt discharging position shown in dotted lines of FIGURE 3.

The ash tray includes the usual inclined bottom portion 14, and front wall 15, as well as relatively straight rear wall 16, and an open top 17, the arrangement being such that when rotated counterclockwise about the first pivots 11 to the position shown in full lines in FIGURE 3, the ash tray is completely contained within the recess in the dashboard and the front wall 15 is substantially flush with the remainder of the panel.

The extinguishing device of the instant invention comprises a flat wall clearing heavy plate 20, which is provided on the bottom thereof with aligned apertured lugs 21 through which extend a pivot rod 22 which is journaled about midheight of the sides 23, as indicated at 24 in FIGURE 1. Plate 20 thus has major and minor area portions bounded by 22. The front plate edge, on the minor area portion, is provided with a curved end stop finger 25, the purpose of which will be more fully described hereinafter.

20 A pendant hook shaped resetting or repositioning stiff spring arm 26 has a top bent end portion 28 which is journaled upon pin 27. Pin 27 is held close to the horizontal wall 29 of the ash tray containing recess. The arm 26 in one position (FIGURE 3 full line showing) 25 extends straight down to a point well below the pivot 22 of plate 20, and terminates, after a kink, in an elongated and curved lower portion 30 which is convex with respect to front wall 15.

30 The stop finger 25 of plate 20 is directly in line with end portion 30 of arm 26, as seen in the front view. The finger 25 is also above end portion 30 of arm 26, as seen in the solid line showing in the sectional elevation view.

In the use and operation of the device, with the ash tray in closed position, as shown in full lines of FIGURE 3, a previously crushed cigarette butt may be present between vertical plate 20 and vertical front wall 15. As the device is opened or pulled outward to the dotted line position of FIGURE 3, however, the arm 26, being fixedly top pivoted at 27 and being located between heavy plate 20 and front wall 15, is allowed to swing counterclockwise as the front wall moves away from the vertical. Pivot 22 simultaneously arcuately moves rightward about 11 thus compelling the base of 26 to keep contact with 15. As arm 26 is now inclined from the vertical, plate 20 is forced out of vertical, and as the center of gravity of plate 20 is always to the left of the pivot 22 (FIGURES 3 and 4) the plate by its own weight starts to swing counterclockwise. Simultaneously the right end 20a of plate 20 engages the curved portion of arm 26 and keeps the arm bottom in contact with the front wall 15.

In the operative position of FIGURE 4, a fresher cigarette butt may be inserted into the open top 17 of the tray, and the butt will be retained in the V between plate 20 and wall 15. To crush all such material the tray may 55 be swung back to the closed position (solid line showing in FIGURE 3), and to discharge all such material to the bottom of the tray, the tray may be swung down to the maximum open discharge position (dashed line showing in FIGURE 3).

60 In this maximum open discharge position, the plate 20 slopes downwardly towards the back 16 and bottom 14 of the ash tray. In this position, stop finger 25 rests against the front wall 15 and the curved end 30 of arm 26 engages both wall 15 and the bottom front portion of stop member 25.

65 After discharging, the tray may be moved inwardly towards closed position. The upwardly moving front wall 15 then contacts the curve 30 of the arm 26 and pushes 70 30 leftwardly (dashed structure of FIGURE 3), whereupon the opposite or left side or toe of the bottom of this arm 26 will engage the stop 25 under the plate 20 and

move the extinguishing plate clockwise (FIGURE 3) until the plate slopes down forwardly instead of rearwardly. Contact between stop member and arm is lost at this latter position, but the right or small lever portion 20a of the plate is then contacting the curve of the arm in an acute angle relationship (FIGURE 4).

At this position, as indicated above, a cigarette butt can be fed through the open top 17 to between front wall 15 and extinguishing plate 20.

Continued closing movement of the tray will force the small lever portion 20a of the plate downwardly, thus causing the plate to approach a vertical position.

The plate 20 next contacts the arm 26 at the lower extremity of its straight portion and the beginning of the curved portion, and upon further tray closing movement the straight portion of the arm slides downwardly past the level of the plate pivot onto the short lever portion of the plate. The springiness of the arm and continuing contact of front wall and arm bottom maintains this contact as the front wall and plate approach vertical parallelism, wherein they are closely adjacent and are capable of compressing portions of cigarette butts priorly placed there-between.

The ash tray removably slides into the recess in the dashboard in any conventional manner (such as by sliding 11 along grooves 31), so that the tray may be removed for emptying as necessary. The arm 26 may be raised completely free of the tray when the tray is pulled out and down at the same time arm 26 is raised, thus allowing the tray to be emptied. At all other times the arm 26 hangs freely from wall 29 of the containing recess.

From the foregoing it will now be seen that there is herein provided an improved extinguisher for cigarette butts adapted particularly for use with motor vehicle ash trays of the pivotal variety, which accomplishes all the objects of this invention, and others, including many advantages of great practical utility.

As many embodiments may be made of this inventive concept, and as many modifications may be made in the embodiment hereinbefore shown and described, it is to be understood that all matter herein is to be interpreted merely as illustrative, and not in a limiting sense.

I claim:

- (1) In combination with a vehicle ash tray pivotally mounted about a fixed horizontal axis in a recess in a vehicle dashboard,
- (2) said tray having an open top, a front wall, and a pair of parallel side walls perpendicular to said front wall,
- (3) an extinguishing plate within said tray and near said front wall, and pivoted about a transverse horizontal axis, all points of the latter axis being at a constant perpendicular distance from said front wall and above said horizontal recess axis,
- (4) said extinguishing plate being movable to a first vertical position parallel to and adjacent said front wall in closed tray position for crushing out a cigarette butt, and also movable to a second position more remote from said front wall and inclined downwardly and away therefrom to dump the butt,
- (5) means for moving said plate into the dumping direction upon opening said tray a maximum amount,
- (6) stop means projecting from one side of said plate, for limiting the movement thereof in the dumping direction by contact of the stop means with said front wall,
- (7) and pendant arm means for pressing against said plate stop means and then against the edge of said plate nearer said front wall, to pivot the plate from the dumping position towards a compressing position in cooperation with the front wall as the tray pivots about said fixed horizontal axis towards a closed position.

2. The structure of claim 1 wherein said pendant arm is mounted at its top in said recess above the tray so as

to swing about a horizontal axis adjacent the front of the recess, and the arm being located closely behind the closed position of the front wall and partly in contacting adjacency with said vertical plate at closed tray position, said arm having a straight upper portion extending down to the bottom edge of the vertically positioned plate, a kink therebelow and a final convexedly curved end, the latter curved arm end contacting one inside face of the plate in all open positions of the tray, and the upper straight portion of the arm contacting for its full width one face of said plate only upon nearing closed tray position.

3. (1) In combination with a vehicle carried cigarette ash tray, pivotally mounted about a first horizontal lower axis means in a flat topped recess in a vehicle dashboard, the latter possessing a vertically inclined upper face, the tray having an open top, a closed bottom wall, a front wall, a rear wall parallel to the front wall and a pair of parallel side walls, the latter pair of walls extending perpendicularly from said front wall,

(2) an extinguishing plate within said tray of such rectangular size and shape as to be movable with clearance with respect to said front, back and side walls, and of such width as to reach the open tray top when the tray is closed,

(3) a second horizontal axis pivot means on one face of said plate, near the plate edge closest to said front wall of said tray thus dividing the plate into a major area portion and a minor area portion, said second pivot means passing at its ends through a substantially midheight portion of each side wall and being parallel to said front wall,

(4) a hook shaped pendant arm means pivotally secured to the flat top structure providing the recess and, in closed tray position, contacting by a straight portion both the minor and major area portions of said plate, and also contacting, by a lowermost portion thereof located mostly below the vertical plate, the adjacent vertical front wall, when the latter is vertical in a closed position of the tray,

(5) whereby said plate is urged to retain said vertical position, and to compress cigarette material inserted between said plate and said front wall.

4. (1) The structure of claim 3 wherein,

(2) said extinguishing plate possesses a stop finger means extending outwardly away from the rear of said plate and directly adjacent said second pivot means, of such length that when the plate has been lowered from vertical to a backward and downward sloping discharge position by tray movement from closed to maximum open position, the curved end of the stop finger contacts the inside of the front wall of the tray, and the edge portion of the plate adjacent said minor area portion is spaced away from the inside of the front wall of the tray.

5. (1) The structure of claim 4 wherein, in discharge position

(2) the lowermost and curved portion of the pendant arm is shaped so that from its upper portion downward it first is clear of the lower edge of the minor area portion of the plate and the front wall, then at a lower portion the curve contacts only the inside of the front wall, and finally at a lowest portion of the curve the arm end contacts the stop finger only,

(3) whereby upon closing movement of the tray, the lower curved portion of the arm is forced towards the stop finger, thus raising the plate to a position in which it is sloping downwardly and frontwardly.

6. (1) The structure of claim 5 wherein

(2) the width of the minor area portion of the plate is such, and the upper part of the curve on the arm is such that, upon continued closing movement of the tray, the plate end most distant from the arm continues to rise as the tray approaches a vertical position,

(3) and finally as the front of the tray is vertical and the tray is closed, the plate is forced into a vertical position with a space between itself and the inside of the tray whereby material therebetween is subject to a crushing pressure.

7. (1) In combination with a vehicle ash tray pivotally mounted at a lower location within a lower portion of a flat top recess in a vehicle dashboard,

(2) said tray having an open top, a planar uniform height transverse front wall, a back wall substantially parallel to the front wall having a uniform top edge at a lower level than that of the front wall, the front wall in closed tray position extending vertically from adjacent the top of the recess to near the level of said pivotal mounting,

(3) a pendant arm spaced slightly inwardly from the inside of said front wall and freely pivoted at its top adjacent to the flat top of the recess to move about a horizontal transverse axis parallel to said front wall,

(4) said pendant arm in closed tray position extending straight downwardly a certain distance, then abruptly bent towards the front wall, and then curved reversely at its bottom in an arc, such that a convex portion of the arcuate bottom abuts the front wall and a terminal portion is directed away from said front wall,

(5) an extinguishing plate pivotally mounted in the tray on a transverse horizontal axis pivot rod near one edge and on a side of the plate more distant from the front wall, said extinguishing plate, in closed tray position, being held vertically upright with said one edge directed downwardly by contact with the lower portion of said straight part of said pendant arm,

(6) a curved end stop finger projecting from the side of the plate remote from the front wall in closed tray position and located adjacent the plate pivot rod, the stop finger defining a plane in transverse alignment with said pendant arm,

(7) whereby upon movement of the tray from closed towards open position, the top of said pendant arm overbalances said extinguishing plate from a vertical position causing the plate to move its top edge towards the back wall, this movement appearing as counterclockwise from one transverse observation position, this counterclockwise motion continuing as the tray is opened until said stop finger con-

tacts the front wall at which position the plate is sloping downwardly and toward the back wall to discharge debris into the ash tray,

(8) the pendant arm during this counterclockwise motion of the plate, also performing a counterclockwise motion of lesser angular extent as compared to the plate, since the lower portion of the arm is guided between said one plate edge and the front wall of the tray,

(9) and whereby upon moving the tray from discharge position towards closed position, the upward motion of the front wall causes contact with the curve of the pendant arm thus originating a clockwise motion of said arm, resulting in continuing contact between the end of the arm and the stop member under the extinguishing plate and causing a consequent clockwise movement of said plate to above a horizontal position,

(10) during further closing movement of the tray, the end of the pendant arm escapes below and out of contact with the stop finger but at this phase of movement said one end of said plate nearer the front wall engages the curve of the arm at an acute angle and this engagement with further clockwise arm movement raising the plate to nearly vertical position, such that the plate and front wall are in cigarette butt receiving positions,

(11) and upon final closing movement of the tray from cigarette butt receiving positions to fully closed position, the abrupt bend of the pendant arm contacts the said nearer edge of the plate and moves downwardly therealong to position the plate in continuing greater proximity to a vertical position to an exactly vertical simultaneous alignment of plate and front wall at closed position of the tray, whereby to compress a cigarette butt placed priorly therebetween.
